UNITED STATES PATENT OFFICE.

MADISON D. SHIPMAN, OF DEKALB, ILLINOIS.

WIRE FENCING.

SPECIFICATION forming part of Letters Patent No. 707,455, dated August 19, 1902.

Application filed April 28, 1897. Renewed April 14, 1902. Serial No. 102,859. (No model.)

To all whom it may concern:

Be it known that I, MADISON D. SHIPMAN, a citizen of the United States, residing at De-
kalb, in the county of Dekalb and State of
5 Illinois, have invented certain new and use-
ful Improvements in Wire Fencing; and I do
declare the following to be a full, clear, and
exact description of the invention, such as
will enable others skilled in the art to which
10 it appertains to make and use the same, ref-
erence being had to the accompanying draw-
ings, and to the figures of reference marked
thereon, which form a part of this specifica-
tion.

15 My invention relates to wire fences, and has
special reference to the manner of uniting or
tying the intersecting wires forming the fence.

The objects of my invention are to provide
a strong, durable, efficient, and simple con-
20 nection of the vertical tie-wires with the lon-
gitudinal wires or cables and to produce a
wire-fence fabric which can be cheaply made
and easily attached to the fence-posts. I at-
tain these objects by means of the construc-
25 tion shown in the accompanying drawings, in
which—

Figure 1 is a side elevation of a fence con-
structed in accordance with my invention.
Fig. 2 is a perspective view of a section of
30 the longitudinal cable and showing the man-
ner of connecting the vertical stay-wires
thereto. Fig. 3 is a section through the cable
and showing the manner of clamping the
stay-wires thereto. Fig. 4 is a plan view of
35 the same.

In said drawings the numeral 1 designates
the longitudinal cables, 2 the fence-posts, and
3 the vertical tie-wires. The longitudinal

cables are shown as made up of two strands
twisted together, and any suitable number of 40
these cables may be used in making up the
fence fabric. The vertical stay or tie wires
are connected to the cables by loops 4, formed
in the stay-wires, said loops being passed be-
tween the twisted strands and tightly clamped 45
around one of the strands of the cable. As
shown in Fig. 3, the crown of the loop is
passed between the strands of the cable and
bent around to closely hug one of the strands,
the dotted lines in said figure showing that 50
the crown of the loop may be bent around
either strand of the cable.

It will be noticed that the loops 4 may be
formed in the stay-wires without requiring a
free end, and this is a matter of considerable 55
importance in forming a fence fabric in a
continuous web, as it dispenses with the extra
expense of cutting and carrying the free ends
of the wires at every loop or tie.

The longitudinal cables may be made of 60
any suitable number of strands. Barbs may
be secured to the longitudinal strands of
fences by the loops 4.

I claim—

In a wire fence, the combination of twisted 65
wire cables and intersecting tie-wires, the
latter having loops, the crowns of which are
passed between the strands of the cable to
closely embrace one of said strands.

In testimony whereof I affix my signature 70
in presence of two witnesses.

MADISON D. SHIPMAN.
